SHAPING DIE

Marshall Steder, Chicago, Ill., assignor to L. J. Miley Company, a corporation of Illinois

Application February 27, 1947, Serial No. 731,364

7 Claims. (Cl. 153—48)

1

This invention relates to a shaping die, and particularly to a die for bending a piece of material having a web and a base portion attached thereto so that the base portion is of arcuate shape with the web on the inside of the arc.

The present invention is particularly designed for forming brake shoes from straight pieces of a steel T-bar. The brake shoes are formed by bending the base of the T in an arcuate shape corresponding in curvature to the inside of the brake drum while maintaining the web of the T in a single plane with the web on the inside of the arc. This was formerly done by using a fixed die with the web of the T fitting into a slot in the die and the base of the T being tangent to a curved shaping surface of the die. Pressure was then applied to the base to bend it against the shaping surface. It was found, however, that there were a large number of the brake shoes that had to be rejected because of wrinkling of the web. This was caused because of the fact that steel T-bars were not uniform in thickness and some of the webs were too narrow to completely fill the slot. Ordinary mill steel has tolerances of $\pm .005$ inch. Wrinkles are also caused by the die surface wearing during use and thus causing the wrinkles to get progressively worse.

One feature of this invention is the provision of the improved shaping die for making brake shoes or the like wherein wrinkling of the web is prevented; another feature of the invention is the provision of a shaping die having one die member made in two parts and movable toward and away from each other with means for holding the web therebetween. Other features and advantages of the invention will be apparent from the following description and the accompanying drawings.

Of the drawings, Fig. 1 is a front elevation of one embodiment of the invention with portions broken away for clarity of illustration; Fig. 2 is a vertical section taken along line 2—2 of Fig. 1; Fig. 3 is a front elevation of another embodiment of the invention; and Fig. 4 is a side elevation of the embodiment shown in Fig. 3.

In the embodiment shown in Figs. 1 and 2 the shaping die comprises a male or first die member 10 and a female or second die member 11. The first die member 10 is made in two parts 10a and 10b by a central dividing plane. One part 10a is fixed to a base 12. The other part 10b is movably supported on a depressed surface 12a in said base so that it is movable toward and away from the fixed part 10a. Both die parts 10a and 10b have an arcuate curved surface 10c that has

2

the same curvature as that of the finished brake shoe. Extending between the two die parts 10a and 10b are three compression springs 13 serving as means normally urging the two parts away from each other. Each spring 13 is seated in two aligned cavities 10d with both cavities being located in a die part 10a and 10b. Three of these springs 13 are provided with each spring forming the angle of an isosceles triangle. Means are also provided for limiting the extent of movement caused by the springs. As shown, this means comprises a pair of shoulder screws 14 with each screw extending through the movable die part 10b and engaging threads in the fixed die part 10a. Each screw has an enlarged head portion 14a held within a countersunk hole on the outer surface of the movable die part 10b. This serves to limit the outward movement of the movable die part 10b and the distance of movement may be regulated by regulating the effective length of the shoulder screws 14.

Attached to the base 12 extending upwardly there is located a stop member 15. This stop member is located at the exact distance from the center of the first die member 10 so that a T-bar 16 placed on the first die member will abut against the stop member 15 and be automatically locked in the correct position for bending. As shown in Figs. 1 and 2, the T-bar 16 is positioned with its web 16a extending downwardly between the die parts 10a and 10b while the base 16b of the T-bar rests on top of the curved shaping surface 10c. The effective length of the shoulder screws 14 is such that the web 16a may be easily placed between the die parts, but will have a snug fit therein.

In order to apply pressure to the T-bar 16 and bend it around the curved surface 10c, the second die member 11 is provided with a hollowed interior 17. This hollowed interior is arranged to press the base 16 of the T-bar against the surface 10c and to press the side portions of the web 16a between the first die parts 10a and 10b. The second die member 11 also has a dual function of pressing the die parts 10a and 10b together to apply pressure on the web 16a and prevent its wrinkling. This is done by having the outer surface of the parts 10a and 10b sloping gradually outwardly from the top to the bottom. The sides of the hollowed interior are similarly sloped from the innermost point to the outer edge. The outer edges 11a are also slightly rounded. By having these side surfaces carefully machined so that the slopes are the same and gradual, a cam action is provided forcing the two die parts

10a and **10b** together to hold the web **16a**. Although as pointed out above successive T-bars **16** will vary somewhat in thickness, the amount of pressure applied is so great that a T-bar having a web of excessive thickness will be compressed due to the elasticity of the metal and will be bent without wrinkling the web **16a**. This is also true of those T-bars whose thicknesses are slightly smaller than the average.

In using the shaping die, the T-bars **16** are first cut to the required length. A cut bar is then placed on the first die member **10** in the position shown in Figs. 1 and 2 with one end of the bar in contact with the stop member **15**. The second die member **11** is then brought down over the first die member **10**. This forces the first die parts **10a** and **10b** together to hold the web **16a** of the bar against wrinkling, bends the base **16b** of the T on to the surface **10c** and forces the side parts of the web **16a** between the die parts **10a** and **10b**.

In the embodiment shown in Figs. 3 and 4, the first die member **110** is formed of two parts **110a** and **110b** being movable toward and away from the part **110a**. The fixed part **110a** is fastened to a base **112** and is also provided with a backing member **120**. Spring **113** similar to the springs **13** previously described are provided between the two die parts **110a** and **110b** except in this instance only two springs are shown. The movable die member **110b** is moved toward the fixed die member **110a** by means of a crank **121** having threads **121a** on one end engaging similar threads in a base member such as a block **122** and bearing against the movable die member **110b**. The movable die member is moved by turning the crank **121** by means of the crank handle **121b**. A stop member **115** is also provided for locking the T-bar **116** in its proper position. In order to bend the T-bar **116** a second die member **111** is provided shaped similarly to the previously described die member **11** except for having cut out portions **111a** and **111b** at the bottom passing around the backing member **120** and the block **122** respectively when the second die member **111** is forced down on the first die member **110**.

In operating the embodiment shown in Figs. 3 and 4, the section of the T-bar **116** is placed on top of the first die member **110** in the manner previously described, the crank **121** is turned to force the movable die part **110b** toward the fixed die part **110a** and hold the web of the T-bar therebetween. The second die member **111** is then forced down over the first die member **110** to bend the T-bar **116**.

The two die members may be forced together in any manner desired, but because of the large pressure employed, ordinarily 100 pounds per square inch or more, this is usually accomplished by a conventional hydraulic ram.

In the embodiment shown in Figs. 3 and 4, the movable die part **110b** is caused to move toward the fixed die part **110a** by the crank **121**. Other means may, of course, be used so long as pressure may be quickly and easily applied to the movable die part **110b**.

Having described my invention as related to the embodiments shown in the accompanying drawings, it is my intention that the invention be not limited by any of the details of description unless otherwise specified, but rather be construed broadly within its spirit and scope as set out in the accompanying claims.

I claim:

1. A shaping die for bending a piece of mate-

rial having a web and a base portion attached thereto, said die comprising: a first member having an edge surface shaped to conform to the intended shape of the base portion and a pair of opposite side surfaces, said first member being made of two parts formed by a central dividing plane and relatively movable toward and away from each other to hold the web therebetween; and a second member having a surface for pressing the base portion of the material against said surface of the first member and a pair of inner side surfaces for simultaneously pressing said two parts toward each other to grasp the web.

2. A shaping die for bending a piece of material having a web and a base portion attached thereto, said die comprising: a first member having an edge surface shaped to conform to the intended shape of the base portion and a pair of opposite side surfaces, said first member being made of two parts formed by a central dividing plane and relatively movable toward and away from each other to hold the web therebetween; and a second member having one surface for pressing the base portion against said surface of the first member and two oppositely disposed inner side surfaces for engaging said side surfaces on the first member and press said two parts toward each other to grasp the web.

3. A shaping die for bending a piece of material having a web and a base portion attached thereto, said die comprising: a first member having an edge surface shaped to conform to the intended shape of the base portion and a pair of side surfaces, said first member being made of two parts formed by a central dividing plane and relatively movable toward and away from each other to hold the web therebetween; and a second member having a surface for pressing the base portion of the material against the shaping surface of the first member and a pair of oppositely disposed inner side surfaces for engaging the side surfaces of the first member and simultaneously press said two parts toward each other to grasp the web.

4. A shaping die for bending a piece of material having a web and a base portion attached thereto, said die comprising: a first member having an edge surface shaped to conform to the intended shape of the base portion and a pair of side surfaces, said first member being made of two parts formed by a central dividing plane and relatively movable toward and away from each other to hold the web therebetween; and a second member having a surface for pressing the base portion of the material against the shaping surfaces of the first member and a pair of oppositely disposed inner side surfaces for engaging the side surfaces of the first member and simultaneously press said two parts toward each other to grasp the web; means normally urging the two parts away from each other; and means limiting the extent of said movement.

5. A shaping die for bending a piece of material having a web and a base portion attached thereto, said die comprising: a first member having an edge surface shaped to conform to the intended shape of the base portion and a pair of side surfaces, said first member being made of two parts formed by a central dividing plane and relatively movable toward and away from each other to hold the web therebetween; a hollow second member having an inner surface for pressing the base portion of the material against the shaping surface of the first member and a pair of oppositely disposed inner side surfaces

for engaging the side surfaces of the first member and simultaneously press said two parts toward each other to grasp the web; means normally urging the two parts away from each other; and means limiting the extent of said movement to a distance wherein said pair of surfaces of the first member is not further apart than the corresponding surfaces on the second member.

6. A shaping die for bending a piece of material having a web and a base portion attached thereto, said die comprising: a first member having one surface shaped to conform to the intended shape of the base portion and a pair of side surfaces, said first member being made of two parts formed by a central dividing plane and relatively movable toward and away from each other to hold the web therebetween; a second member having a surface adapted to press the base portion of the material against the shaping surface of the first member and a pair of oppositely disposed surfaces adapted to engage the side surfaces of the first member and simultaneously press said two parts toward each other to grasp the web; means normally urging the two parts away from each other; and means limiting the extent of said movement to a distance wherein said pair of surfaces of the first member is not further apart than the corresponding surfaces on the second member, said pair of surfaces on the first member being slightly sloped toward each other from the base to the top of the first member and said pair of surfaces on the second member being similarly slightly sloped away from each other from their innermost edge to their outermost edge.

7. A shaping die for bending a piece of material having a web and a base portion attached thereto so that the base portion is convex on

the side opposite the web, said die comprising a male member having a curved outer surface shaped to conform to the intended shape of the base portion and a pair of side surfaces slightly sloping away from each other from said curved surface to the base of the male member, said male member being made of two similar parts formed by a central dividing plane and relatively movable toward and away from each other to hold the web therebetween; a female member having a cavity adapted to fit over the other die member and having an inner surface shaped similarly to said curved surface and adapted to press the base portion of the piece of material against said curved surface, and side surfaces having the same slight slope away from each other from the inner surface outwardly and adapted simultaneously to force said two parts together to grasp the web; means normally urging the two parts away from each other; and means limiting the extent of said movement to a distance wherein said pair of surfaces of the male member is not further apart than the corresponding surfaces on the female member.
